UNITED STATES PATENT OFFICE.

THOMAS L. LAWTON, OF PHILADELPHIA, PENNSYLVANIA, ASSIGNOR TO JOHN DUNLAP & SONS, OF SAME PLACE.

DESIGN FOR CARPET.

SPECIFICATION forming part of Design No. 25,431, dated April 21, 1896.

Application filed January 11, 1896. Serial No. 575,179. Term of patent 31 years.

To all whom it may concern:

Be it known that I, THOMAS L. LAWTON, of the city of Philadelphia, county of Philadelphia, State of Pennsylvania, have invented and produced a new and original Design for Carpets, of which the following is a specification.

The nature of my design is fully represented in the accompanying india-ink drawing, to which reference is made.

I claim—
The design for a carpet as herein shown and described.

THOMAS L. LAWTON.

Witnesses:

WM. G. SLAUGH,
GEO. V. SAUER.
